MEASURING INSTRUMENT AND MARKER
COMBINED

Benjamin P. Boston, Pine Wood, S. C.

Application March 9, 1950, Serial No. 148,550

2. Claims. (Cl. 33—42)

1

The present invention relates to certain new and useful improvements in a measuring instrument and marker which latter is mounted on and carried by the measuring instrument whereby to provide the user with a unitary instrumentality for expeditiously laying out work.

Although the aforementioned measuring instrument may be in the form of a graduated rule or the like, it preferably takes the form of a square such as used by carpenters and others, and the marker preferably takes the form of a conventional lead pencil. The novel phase of the invention, however, has to do with a square having an especially constructed leg, a holder for the pencil which permits the pencil to be extended and retracted, and an adapter for said holder whereby the latter may be accurately and operatively mounted on said leg.

Another object of the invention is to provide a multi-purpose instrumentality wherein manufacturers and users will find their most essential needs fully met, contained and effectively available.

Another object of the invention is to provide a square whose long leg is provided with a slotted keying channel in which a ball bearing-equipped slide is keyed for operation, said slide serving as a reciprocable mount for a plate in shiftable contact with said leg and said plate serving as an indicator for coaction with scales on the leg and also as a base and carrier for the pencil holder.

More specifically, novelty is predicated on a leg of the aforementioned construction wherein the opposite longitudinal edge portions of the visible face of the leg have duplicated scales, the latter being parallel to and on opposite sides of the slot, the stated adapter plate having suitably constructed indexes simultaneously registering with corresponding graduations on their respective scales. Then, too, novelty is thought to reside in providing the leg along one longitudinal edge with an outstanding guide flange which serves as an accommodation track for assembling and guide hooks which are carried by one end portion of the stated plate.

What is more, the pencil holder, which preferably takes the form of a cylindrical sheath or casing is thought to be novel in that it correctly locates the point of the pencil in respect to the coacting index on said plate and serves additionally to properly house the pencil, return spring for the pencil and ejecting plunger which, urged by finger pressure, serves to project and hold the pencil against the work while the desired measured mark is being made.

2

Other objects and advantages will become more readily apparent from the following description and the accompanying illustrative drawings.

In the accompanying sheet of drawings, wherefore like numerals are employed to designate like parts throughout the views:

Fig. 1 is a top plan view of a square and marker constructed in accordance with the principles of the instant invention; and

Fig. 2 is a cross section, with parts in elevation, taken on the line 2—2 of Fig. 1, looking in the direction of the arrow.

In general overall appearance the square is the conventional L-type and includes a short leg 4 and a long leg 6. Parts 4 and 6 are sometimes referred as arms, limbs, blades and so on. It is believed, however, that the expression "legs" is an acceptably descriptive term. At one end and on one edge the leg 4 is mortised as at 8 and the coacting end portion 9 of the leg 6 is fitted and secured in the mortise. The reason for this will be later explained. The body portion 10 of leg 6 is centrally provided in its underside with a groove 12 constituting a keying channel. This channel opens through the top surface 14 of the leg by way of a slot 16. The slot and groove are commensurate in lengths. It will be noticed that the left-hand end of the channel and groove extend into the mortised portion 8 of leg 4 as shown in Fig. 1. The bottom of the channel is closed by a cover member 18 which is preferably screwed to the body member 10. A simple slide is employed and this comprises an especially constructed bolt whose square head 20 fits snugly but slidably in the channel. The screw-threaded stud 22 extends through and beyond the slot and has a clamping nut 24 thereon. The head has appropriate indentations to accommodate a plurality of anti-friction balls 26 and 28 which facilitate the movement of the slide from end to end of the channel. In this connection it might be noted that the right-hand ends of the slot and channel terminate inwardly of the right-hand end portion 30 of leg 6. Thus this end of the channel is closed and the opposite left-hand end is open to facilitate assembling of the slide at the time of manufacture.

Referring to Fig. 1 it will be observed that the straight edge 32 which runs parallel to the slot 16 is provided with a suitably graduated scale 34. The straight edge on the opposite side at 36 is provided with a complementary scale 38 and the graduations of the two scales are duplicated.

Attention is now directed to the flat adapter plate 40. This is of general rectangular form and rests slidably on the surface 14. One end is

fashioned into a pointed index 42 to coat with the graduations on scale 34. The opposite end portion is provided with a triangular aperture 44 whose vertex constitutes a second index which cooperates with the graduations on scale 38. The opening permits the graduations to be seen therethrough as shown in Fig. 2. These two indexes 42 and 44 are in obvious alignment with each other and serve to simultaneously coat with the graduations on their respective scales. The last-named apertured end portion of the plate 40 is provided with assembling hooks 46-46 which is slidably engaged with an outstanding flange 48 along the edge portion 36 of leg 6. The plate is also provided with an aperture to accommodate the extending end portion of the shank 22 of the bolt as shown in Fig. 2 and said plate is secured in place by the clamping nut 24. Thus the slide becomes a slidable mount for the plate and the plate becomes an indicator for the scale as well as an adapter for the pencil holder 50. Obviously, the hooks 46 engaging the flange 48 serve to maintain the plate 40 accurately on the scale-equipped face of the leg 6.

The stated pencil holder 50 is a cylindrical or corresponding sheath which is at right angles to and mounted integrally on the indicator plate and is stabilized by suitable bracing flanges 51. The cylinder 52 is provided at its bottom with a centrally apertured flange 54 which serves to hold in place a fiber sleeve 56 which constitutes a friction holder for the extensible and retractable pencil 58. A plunger 60 is slidably mounted in the sleeve 62 carried by a cap 63 screwed on one end portion of the sheath and has a knob 64 which provides an appropriate grip or push button. The cup portion 66 of the plunger, which is inside of the casing, is in thrust engagement with the pencil to force the pencil out when it is needed for marking purposes. A coiled spring 68 surrounds the pencil and is appropriately mounted in the sheath or casing to return the pencil to its retracted position, once the marking work has been complete.

It is evident that by permanently attaching the projectable and retractable pencil in a suitable holder and slidably mounting the holder on the measuring instrument, the slide may be shifted back and forth for measuring purposes and the pencil will move in conjunction therewith. Thus, the line to be marked will be in relation to the scale markings or graduations and the graduations on the scales are observable by way of the indexes 42 and 44. The index 44 obviously points to and locates the longitudinal center line of the marking pencil 58.

It will be further noted that by mortising the end portion 9 of the leg 6 in the mortised end of leg 4 sufficient "clearance" is had to permit the scale markings to begin at zero, using the edge 10 of the leg 4 as the point of orientation for both scales. Also, the channel and slot extend beyond the graduations "6" at the ends of the two scales to allow the slide to move sufficiently far to the right to allow the indexes 42 and 44 to register with said markings "6."

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

5 Having described the invention, what is claimed as new is:

1. A structure of the class shown and described and comprising a square including a leg having a longitudinally extending groove with a entrance slot, having a measuring scale along at least one longitudinal edge portion, said scale being parallel to said slot, a slide mounted in said groove and having a screw-threaded stud projecting operatively through said slot, a flat indicator plate in contact with and freely shiftable along the slotted surface of said leg and detachably mounted on said stud, said plate having indexes lined up with graduations on said measuring scale, and a marking pencil and holder therefor carried by and at right angles to said plate, one edge of said leg having an outstanding guide flange and the corresponding edge of said plate being provided with assembling and guiding hooks slidably mounted on said flange.

2. In a structure of the class described, in combination, a measuring instrument having a leg provided with parallel straight edges and graduated scale means, said leg having a central longitudinal channel opening through one transverse end of the leg and having its opposite end closed and terminating inwardly of the remaining transverse end of the leg and having a slot opening from the channel through the scale-equipped surface of said leg, a slide operable in said channel and having a screw-threaded shank extending through and beyond the slot, a flat plate slidably contacting the scale equipped surface of the leg, said plate having an opening therein and said shank extending through said opening, a nut on said shank detachably clamping the plate to the shank, said plate having a pointed index at one end and having a triangular opening providing a second index for coaction with the graduations of said scale means, said leg being provided along one longitudinal edge with a tracking flange, the adjacent end portion of said plate having hooks slidably engaging said flange, and pencil holding means mounted on the hook-equipped end of said plate, said pencil holding means comprising a cylindrical sheath formed integral with said plate and extending at right angles therefrom and a spring-returnable plunger slidably mounted in said sheath.
